US00D612734S

(12) United States Design Patent
Sarsfield-Thomas et al.

(10) Patent No.: US D612,734 S
(45) Date of Patent: * Mar. 30, 2010

(54) BOTTLE

(75) Inventors: Mary Sarsfield-Thomas, New Milford, CT (US); William Eaton, Purchase, NY (US); Taek Kim, Washington Township, NJ (US); Stuart M. Leslie, Larchmont, NY (US); Jason Billig, Mount Vernon, NY (US); David Michael Ryan, Toledo, OH (US); Lori E. Bartman, Sylvania, OH (US); Robert Jon Groll, Oregon, OH (US); Richard Allan Lovelace, Jr., Munroe Falls, OH (US); James J. Miller, Barberton, OH (US)

(73) Assignee: PepsiCo, Inc., Purchase, NY (US)

() Term: 14 Years

(21) Appl. No.: 29/325,793

(22) Filed: Oct. 6, 2008

(51) LOC (9) Cl. 09-01

(52) U.S. Cl. D9/516; D9/575

(58) Field of Classification Search D9/682, D9/685, 693, 694, 516, 520, 522, 523, 526, D9/527, 528, 530, 531, 536, 541, 543, 559, D9/560, 564, 565, 569, 570, 571, 575; 215/381-385
See application file for complete search history.

(57) CLAIM

The ornamental design for a bottle, as shown and described.

DESCRIPTION

FIG. 1 is a top, front, left perspective view of a bottle showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The dashed line showing in the drawings is for illustrative purposes only and forms no part of the claimed design. The dot-dash-dot line showing in the drawings defines the boundary of the claim and forms no part of the claimed design.

1 Claim, 6 Drawing Sheets
